VINCENT J. O'BRIEN AND ROMEO C. AWKERMANN, OF DENVER, COLORADO, ASSIGNEES
TO THE STANDARD ROCK DRILL COMPANY, OF DENVER, COLORADO, A CORPOR-
ATION OF COLORADO.

VALVE MECHANISM FOR PNEUMATIC TOOLS.

1,020,619.

Specification of Letters Patent. Patented Mar. 19, 1912.

Application filed August 27, 1910. Serial No. 579,382

To all whom it may concern:

Be it known that we, VINCENT J. O'BRIEN and ROMEO C. AWKERMANN, citizens of the United States, residing in the city and county of Denver and State of Colorado, have invented certain new and useful Improvements in Valve Mechanism for Pneumatic Tools; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates generally speaking to improvements in valve mechanism for pneumatic tools, but more specifically to throttle valve mechanism for tools of this character in which a feed bar is employed for holding the steel of a hammer drill against the rock.

One object of the invention is to provide a construction whereby it becomes practicable to supply the feed bar casing with motive fluid under pressure equal to that which is employed to operate the hammer which reciprocates in the cylinder of the machine.

In the construction common to this class of tools, the pressure of the motive fluid which acts upon the piston of the feed bar, is much greater than that which acts upon the hammer for reciprocating the latter, when the hammer is operating slowly. On this account the drill bit in the ordinary construction heretofore in vogue is held against the rock with much greater pressure than is desirable, under the circumstances stated. In our improved construction, the motive

fluid which is fed to the casing of the feed bar and to the drill cylinder, is controlled in such a manner that it passes to a chamber interposed between the throttle valve and the cylinder valve under only such pressure as is necessary to reciprocate the hammer at the desired speed, the motive fluid passing from this chamber simultaneously to the feed bar casing and the drill cylinder. Hence the pressure which is delivered to the feed bar casing can not be greater than that which passes to the cylinder for reciprocating the

hammer. This is a very important feature when it is desired to run the drill slowly or to reciprocate the hammer at a reduced speed as when the material to be drilled is 55 comparatively soft; and under such circumstances it is exceedingly desirable that the feed bar be actuated by the motive fluid at a pressure reduced to correspond with that which is delivered to the drill cylinder. 60

Another feature of our improved construction of valve mechanism is that it allows a portion of the motive fluid which has been used to propel the hammer on its forward movement, to escape directly to the 65 atmosphere. In explanation of this feature it may be said that it is quite common in machines of this class to employ hollow cylindrical valves having differential pressure areas at their opposite extremities, the 70 smaller of which is constantly exposed to motive fluid pressure, and the larger intermittently exposed thereto. In some styles of these tools the motive fluid which has been used to propel the hammer on its forward movement, is still used as motive fluid while passing to the atmosphere in so far as it exerts a pressure against the larger area of the valve sufficient to overcome the 75 constant pressure on the smaller area. We 80 have demonstrated in actual practice that the speed of a machine equipped with the above style of valve, can be increased ten per cent. or more by the use of an auxiliary exhaust controlled by our improved throttle 85 valve. The reason is that the auxiliary exhaust results in a sudden weakening of pressure at the precise time when it is needed, namely, when the hammer is stationary at the end of its forward stroke and about to 90 start on its return trip. In this event after the hammer has moved a short portion of its return trip, it covers the auxiliary exhaust port so that the effect of motive fluid passing to the atmosphere from the larger area 95 of the cylinder valve is not changed. The reason that the auxiliary exhaust of the aforesaid character must be controlled by the throttle valve, is that the auxiliary exhaust must not occur until the machine has 100 reached almost its maximum speed. If this exhaust be allowed to escape directly to the

atmosphere the machine will not work well while running at a slow speed, hence the necessity for controlling it by the use of the throttle valve so that the auxiliary exhaust 5 is only employed when the machine is running at practically its maximum speed.

Having briefly outlined our improved construction, we will proceed to describe the same in detail, reference being made to the 10 accompanying drawing in which is illustrated an embodiment thereof.

In this drawing: Figure 1 is a fragmentary section taken through a hammer drill equipped with our improved throttle valve 15 construction, a part of the hammer cylinder and a part of the feed bar construction being illustrated. In this view the throttle valve is so adjusted that the motive fluid is cut off from the feed bar and the hammer cylinder, the feed bar chamber being in communication with the atmosphere for exhaust purposes. Fig. 2 is a similar view 20 showing the throttle valve in a different position, namely, that in which the motive fluid is delivered to the feed bar chamber, but cut off from the hammer chamber. Fig. 3 is a similar view in which the motive fluid is cut off from direct communication with the feed bar chamber, but allowed to pass 25 to a chamber interposed between the cylinder valve and the throttle valve, the motive fluid passing from the said chamber to the cylinder chamber and feed bar chamber after being properly throttled for the purpose. Figs. 4 and 5 are sections taken 30 through the throttle valve mechanism on lines 4-4 and 5-5 respectively of Fig. 2. Figs. 6 and 7 are sections taken on the line 7-7 Fig. 2, showing the throttle valve 35 in two different positions. Fig. 8 is a section taken through a hammer drill cutting the throttle valve mechanism, the parts, being shown in the position illustrated in Fig. 7, to permit the employment of the auxiliary 40 exhaust.

The same reference characters indicate the same parts in all the views.

Let the numeral 5 designate the cylinder; 6 the hammer; 7 the valve mechanism for 50 controlling the supply and exhaust to and from the hammer cylinder; 8 the casing in which the piston 9 of a feed bar 10 is mounted to reciprocate. Interposed between the valve mechanism 7 and the chamber 12 of 55 the feed bar is our improved throttle valve mechanism, which may be designated in its entirety by the numeral 13. In this construction the numeral 14 designates the valve piece, which is frusto-conical and occupies an opening of counterpart shape formed 60 in the valve block 15. The smaller extremity 16 of this valve piece protrudes beyond the valve block and is equipped with an operating head 17 which is secured thereto by 65 a set bolt 18. In the base of this valve is a

recess 19 which is in communication with a conduit 20 which is screwed into the valve block as shown at 21 and registers with the opening in which the valve piece is journaled. This conduit 20 supplies the motive 70 fluid for operating the reciprocating hammer as well as that which acts upon the feed bar for automatically maintaining the drill bit against the rock. The valve block is provided with three ports 22, 23 and 24 respectively leading from the valve chamber 25 to the chamber 12 in which the feed bar reciprocates; and also with passages 26 and 27, the passage 26 leading from the valve chamber 25 to a supply chamber 28 formed 80 in the valve block adjacent the valve mechanism 7 and communicating with passages 29 formed in the casing 30 and inclosing the valve mechanism 7. The passage 27 also leads from the valve chamber 25 to the supply chamber 28. This chamber 28 enables us to obtain a number of advantages in the 85 operation of the machine. Among these are the following: Since the motive fluid passes from this chamber to both the engine and feed bar casing, the pressure must be the same in both and will always be proportionate in the feed bar casing to the requirement for holding the drill against the rock. This feature has been already mentioned. This 90 chamber 28 also makes it practicable to handle the dirt and foreign matter contained in the motive fluid in such a manner that no harm results to the delicate valve mechanism of the engine, since the dirt contained 95 in the motive fluid passes to the engine at once and in comparatively small quantities, and is much less injurious to that part than when it is allowed to accumulate in the feed bar casing in which latter event it is exceedingly injurious to the feed bar mechanism at all times and to the valve mechanism of the engine whenever the position of the engine is changed so that the feed bar casing is above, whereby the accumulation of 100 dirt and foreign particles of matter is allowed to pass into the engine in comparatively large quantities. Furthermore this chamber enables us to obtain the most speedy and sensitive coaction between the pressure 1 in the feed bar and the speed of the motor; and since a partial closing of the throttle valve and the consuming capacity of the motor are the only factors provided for reducing the pressure in the feed bar casing, 1 it is found in practice that the desired result is attained to the maximum degree by the employment of this chamber. There is still another very important feature of advantage resulting from this chamber since 1 the machine is so balanced that the vibration is greatly reduced. Attention is called to the fact that in our construction the motive fluid is first allowed to pass to the chamber 28 in the head block. It passes 1

thence in opposite directions to the feed bar casing and engine respectively. This gives a balanced result because of the fact that the motive fluid is passing simultaneously in opposite directions to the two instrumentalities, the force of the fluid in opposite directions having a neutralizing effect and greatly reducing the vibration as compared with the result in those constructions in which the motive fluid passes first to the feed bar casing and immediately acts or produces a tendency to move the machine in the rearward direction, so far as the instability of its support will permit, and then as the fluid passes in the opposite direction, there is a resultant vibration produced which is entirely absent in our construction.

The valve piece 14 is provided with U-shaped passage 31 formed in its upper portion and adapted when the valve piece is properly adjusted to register with the passage 24, whereby the motive fluid from the chamber 12 is allowed to escape to the atmosphere, the passage 31 being continued through the operating head of the valve piece as shown at 32. The valve piece is also provided with a passage 33 extending transversely therethrough and adapted when the valve is properly adjusted to register with the passages 22 and 26 of the valve block, to allow the motive fluid to pass from the chamber 28 to the feed bar chamber 12 simultaneously with its passage from the supply chamber 28 to the cylinder chamber for operating the hammer. The valve piece is further provided with a port 34 which when the valve is in the position to cause its passage 33 to register with the passages 24 and 26, opens communication between the annular recess 19 of the valve piece and the passage 27 of the valve block, thus allowing the motive fluid to pass freely from the supply conduit 20 to the supply chamber 28. The valve block is also provided with passages 35 and 36, the latter communicating at its forward extremity with an exhaust passage 37 formed in the wall of the cylinder and the casing 30 of the valve mechanism 7, the forward extremity of the passage 37 communicating by a port 38 with the cylinder chamber 39 just in the rear of the rear extremity of the hammer 6 when the latter is at or approximately at its forward limit of movement. The rear extremity of the passage 36 communicates as shown at 40 with the valve chamber 25. The passage 35 communicates at its forward extremity with the chamber 25 as shown at 41, and at its rear extremity with the atmosphere as shown at 42. When the valve piece 14 is properly adjusted a cavity 43 formed therein places the passages 35 and 36 in communication with each other and consequently with the exhaust passage 37 of

the cylinder, thus opening a continuous passage from the forward portion of the cylinder to the atmosphere.

From the foregoing description the use and operation of our improved throttle valve mechanism will be readily understood. If we assume that the parts are in the position shown in Fig. 1, the throttle valve is adjusted to place the feed bar chamber 12 in communication with the atmosphere by way of the passages 24, 31 and 32. In this case the motive fluid is cut off from the feed bar chamber 12 and the cylinder chamber 39. Now if it is desired to set the drill against the rock, the throttle valve will first be turned to the position shown in Figs. 2 and 5, in which event a short passage 44 formed in the valve piece places the passage 23 of the valve block in communication with the annular recess 19 of the valve, thus allowing the motive fluid to pass to the feed bar chamber 12, whereby the drill bit is pressed against the breast of the rock preparatory to the commencement of the drilling work. Now in order to start the hammer the throttle valve is given a further partial rotation as indicated in Fig. 6, whereby the passages 23 and 44 are cut off from the motive fluid, the valve piece, however, being turned sufficiently to allow the motive fluid to pass to the chamber 28 through the port 34 of the valve, through the passage 27 of the valve piece, and thence from the chamber 28 through the passage 26 of the valve block, the passage 33 of the valve piece, and the passage 22 of the valve block to the feed bar chamber 12. As illustrated in Fig. 6, however, the passage 33 of the valve piece is only partially placed in register with the passages 22 and 26. In this event the hammer will be slowly reciprocated and the auxiliary exhaust is not employed, since the passages 35 and 36 are not placed in communication, the cavity 43 not being in position to connect the passages 35 and 36. Now if it is desired to run the drill at maximum speed, the valve piece will be given a further partial rotation in the same direction, whereby the passage 33 of the valve piece is placed in full register with the passages 22 and 26 of the valve block, the port 34 of the valve piece and the passage 27 of the valve block being also simultaneously placed in full register to allow the maximum quantity of motive fluid to pass from the supply conduit 20 to the supply chamber 28, and thence to the cylinder chamber 29 and the feed bar chamber 12. In this event the movement of the valve piece also places the cavity 43 in position to connect the passage 36 with the passage 35, thus opening a continuous exhaust passage from the forward portion of the cylinder chamber to the atmosphere by way of the port 38, the pas-

sages 37 of the valve cylinder, the passage 36 of the valve block, the cavity 43 of the valve piece and the passage 35 of the valve block. Under these circumstances the hammer 6 will be reciprocated at its maximum speed and the auxiliary exhaust will be utilized as heretofore explained.

Having thus described our invention, what we claim is:

- 10 1. In a pneumatic tool equipped with a feed bar casing, a piston movable therein and a motor, the combination of a head block having a relatively large chamber in communication with the motor and feed bar 15 casing for constantly supplying motive fluid in common to both the said casing and said motor when the latter is in operation, and means for delivering and throttling the motive fluid on its way from the source of supply to said chamber, the latter being located on the opposite side of the throttling means from the feed bar casing, the head block having a passage leading from the said chamber to the said casing.
- 20 2. In a hammer drill equipped with a feed bar casing and an engine, the combination of a head block interposed between the feed bar casing and said engine and having a relatively large chamber in communication 25 with the engine and feed bar casing, the said chamber being arranged to constantly supply motive fluid in common to both the said casing and said engine when the latter is in operation, the head block having a passage leading from said chamber to the feed 30 bar casing, and means located between the said chamber and said casing for delivering and throttling the motive fluid on its way to the said chamber.
- 30 3. In a hammer drill equipped with a feed bar casing and an engine, the combination of a head block interposed between the feed bar casing and said engine and having a relatively large chamber in communication 35 with the engine and the feed bar casing, the said chamber being arranged to constantly supply motive fluid in common to both the said casing and said engine when the latter is in operation, the valve and head block having passages leading from the said chamber to the said casing, and a throttle valve 40 located in the head block for controlling the motive fluid on its way to the said chamber, the latter being located between the said valve and the engine.
- 40 4. In a tool of the class described equipped with a feed bar casing and a drilling engine, the combination of a block interposed between said casing and said engine and having a relatively large chamber in communication 45 with the engine and feed bar casing, said chamber arranged to constantly supply motive fluid in common to both the feed bar casing and said engine when the latter is in operation, a valve journaled in said

block for throttling the motive fluid on its way to said chamber, the latter being located between the said valve and the said engine.

5. In a tool of the class described equipped 70 with a feed bar casing and an engine, the combination of a head block interposed between the said casing and said engine, a throttle valve mounted in said block, the latter being provided with passages located 75 on opposite sides of the valve, and a relatively large chamber in communication with the engine and feed bar casing, the said chamber being arranged to constantly supply motive fluid in common to both the feed 80 bar casing and engine when the latter is in operation, the said chamber being located between the throttle valve and the engine, one of said passages in the head block extending toward the engine and communicating with the said motive fluid supply chamber while the other passage is located on the opposite side of the valve and in communication with the feed bar casing, the valve and head block having a passage for 85 the supply of motive fluid to the said chamber, the valve having a passage adapted to register with the passages in the head block on opposite sides of the valve when the engine is in operation.

6. In a tool of the class described equipped with a feed bar casing and a drill cylinder, the combination of a head block interposed between the said casing and cylinder, and a throttle valve rotatably mounted in said 100 block, the valve and head block having passages for simultaneously regulating the supply of motive fluid to the feed bar casing and the drill cylinder, and for regulating the exhaust from the feed bar casing and 105 drill cylinder.

7. In a tool of the class described equipped with a feed bar casing and drill cylinder, the combination of a head block interposed between the said casing and said cylinder, ports and passages located in the valve and head block for simultaneously regulating the supply of motive fluid to the drill cylinder and feed bar casing as the valve is rotated, the head block also having exhaust 110 passages which are arranged to be placed in communication with each other when the valve is adjusted, the latter having a cavity for the purpose when it is placed in position, to deliver the maximum supply of motive 115 fluid to the feed bar casing and drill cylinder, the said exhaust passages being in communication with the drill cylinder for the purpose set forth.

8. In a tool of the class described equipped 120 with a feed bar casing and a drill cylinder, the combination of a head block interposed between the feed bar casing and drill cylinder, a throttle valve rotatably mounted in said block, and exhaust passages formed in 125

the said block, the said valve having a cavity adapted when the valve is properly adjusted to place the said passages in communication with each other, the wall of the 5 drill cylinder having an exhaust passage leading from the forward portion of the cylinder and communicating with one of the exhaust passages in the head block.

9. In a tool of the class described equipped 10 with a feed bar casing and a drilling engine, the combination of a head block interposed between the said casing and said engine, a valve mounted to rotate in said block, the valve and head block having passages for 15 successively regulating the supply of motive fluid from the source of supply directly to said feed bar casing for setting the drill against the rock and placing the feed bar casing in communication with the atmosphere 20 for exhaust purposes, the head block having a relatively large chamber located adjacent the engine, the valve and head block having passages for conducting the motive fluid from the said chamber to the 25 feed bar casing, for constantly supplying motive fluid to the feed bar casing when the engine is in operation, means for throttling the motive fluid on its way to the said chamber, the latter being external to the throttling means.

10. In a tool of the character described equipped with a feed bar casing and a drilling engine, the combination of a head block interposed between the said casing and said 25 engine, and the head block having a relatively large chamber located adjacent the engine and in communication with the engine and feed bar casing, for supplying motive fluid in common to the said chamber and 40 said engine, and a throttle valve rotatably mounted in said block, the valve and head block being equipped with passages for simultaneously admitting motive fluid to said chamber in the head block and from said 45 chamber to the feed bar casing, and for successively admitting motive fluid directly to the feed bar casing to set the drill against

the rock and for placing said casing in communication with the atmosphere for exhaust purposes.

11. In a tool of the class described equipped with a feed bar casing and drill cylinder, the combination of a head block interposed between the said casing and cylinder and a throttle valve rotatably mounted in said block which is supplied with a relatively large chamber adjacent the drill cylinder, the valve and head block having passages for conducting motive fluid to the feed bar casing to set the drill against the 50 rock, and for simultaneously regulating the supply of motive fluid from said chamber to the feed bar casing, the latter being also in communication with the said chamber, the valve and head block also having passages 55 for regulating the exhaust from the feed bar casing and drill cylinder substantially as described.

12. In a tool of the class described equipped with a feed bar casing and drill cylinder, the combination of a head block interposed between the said casing and said cylinder, ports and passages located in the valve and head block for delivering motive fluid to the feed bar casing to set the drill 70 against the rock, and for simultaneously regulating the supply of motive fluid to the drill cylinder and feed bar casing as the valve is rotated, the head block also having exhaust passages which are arranged to be 75 placed in communication with each other when the valve is adjusted to deliver the maximum supply of motive fluid to the feed bar casing and drill cylinder, the valve having a cavity for the purpose, the said exhaust passages being in communication with the drill cylinder for the purpose set forth.

In testimony whereof we affix our signatures in presence of two witnesses.
